(57) **CLAIM**

The ornamental design for a portion of lighter, as shown and described.

DESCRIPTION

FIG. 1 is a front perspective view of a portion of lighter showing my new design;

FIG. 2 is a front view of the portion of lighter of FIG. 1;

FIG. 3 is a rear view of the portion of lighter of FIG. 1;

FIG. 4 is a right side view of the portion of lighter of FIG. 1;

FIG. 5 is a left side view of the portion of lighter of FIG. 1;

FIG. 6 is a top plan view of the portion of lighter of FIG. 1;

FIG. 7 is a bottom plan view of the portion of lighter of FIG. 1;

FIG. 8 is a front view of the portion of lighter of FIG. 1 showing the movement of nozzle in a smaller angle; and, FIG. 9 is a front view of the portion of lighter of FIG. 1 showing the movement of nozzle in a larger angle.

The broken lines are shown for illustrative purposes only and form no part of the claimed design.
